(57) **CLAIM**

The ornamental design for a packaging container, as shown and described.

DESCRIPTION

FIG. 1 is a top front left perspective view of a packaging container showing our new design;

FIG. 2 is a front view of the design shown of FIG. 1;

FIG. 3 is a rear view of the design shown of FIG. 1;

FIG. 4 is a left side view of the design shown of FIG. 1;

FIG. 5 is a right side view of the design shown of FIG. 1;

FIG. 6 is a top view of the design shown of FIG. 1; and,

FIG. 7 is a bottom view of the design shown of FIG. 1.

The broken lines shown in the figures are included for the purpose of illustrating portions of the packaging container and form no part of the claimed design.

1 Claim, 7 Drawing Sheets(56)
